UNITED STATES PATENT OFFICE

JOSEPH PHILLIPS, OF DENVER, COLORADO

DESIGN FOR A RADIO AND TELEVISION CABINET

Application filed September 15, 1930. Serial No. 36,971. Term of patent 7 years.

To all whom it may concern:

Be it known that I, JOSEPH PHILLIPS, a citizen of the United States, residing at the city and county of Denver, State of Colorado, have invented a new, original, and ornamental Design for Radio and Television Cabinets, of which the following is a specification, reference being had to the accompanying drawings, forming part thereof.

In the drawing:

Fig. 1 is a front view of the cabinet showing my new design, and

Fig. 2 is an end elevation thereof.

I claim:

The ornamental design for a radio and television cabinet as shown.

In testimony whereof I affix my signature.

JOSEPH PHILLIPS.
